UNITED STATES PATENT OFFICE.

ALPHONSO A. WOELFEL, OF CENTRALIA, WASHINGTON.

ALARM-CLOCK.

1,254,956.

Specification of Letters Patent.

Patented Jan. 29, 1918.

Application filed March 14, 1917. Serial No. 154,890.

To all whom it may concern:

Be it known that I, ALPHONSO A. WOELFEL, a citizen of the United States, residing in the city of Centralia, county of Lewis, 5 and State of Washington, have invented certain new and useful Improvements in Alarm-Clocks, of which the following is a specification.

My invention relates to alarm clocks, 10 and more particularly to means, operated by the winding mechanism of the alarm, for automatically releasing the locking mechanism which is used to stop the alarm mechanism after it has commenced to run. It is quite common for a person, after being 15 awakened by an alarm clock, to set the locking mechanism so as to stop the operation of the alarm. It is also quite common, when next winding the alarm for another occasion, 20 to forget to release the locking mechanism, and the alarm, therefore, fails to serve its purpose the next time, because the locking mechanism has not been released. The object of my invention is to provide means 25 in connection with the alarm mechanism of a clock, whereby the winding of said alarm mechanism automatically unlocks the locking mechanism and leaves the alarm in condition to operate at the time for which it is 30 set.

In order to explain my invention I have 35 illustrated one simple and practical embodiment thereof on the accompanying sheet of drawings, which I will now describe.

35 In the drawing, I have shown the back of a standard alarm clock, with a part broken out to show the application of my invention thereto.

In describing the invention I will designate the parts which are old with the letter O with an exponent, or affix, and the parts which are new with the letter N with an exponent, or affix.

Referring now in detail to the drawings, 45 O¹ designates the bell, or alarm instrument, and O² the hammer mounted upon a stem O³, in the usual manner. A locking member O⁴ is pivotally mounted adjacent the stem O³, of the hammer, and when moved into 50 the position shown in full lines, it operates to lock the hammer against operation. In other words, the alarm is shut off. When the member O⁴, is moved to the position shown in dotted lines, it is clear of the hammer stem O³, and the alarm is free to operate. The usual winding keys O⁵ and O⁶, are

shown; the winding key O⁵, controlling the usual clock movement, while the winding key O⁶, controls the alarm-operating movement.

My invention comprises a link N¹, connected at one end to the locking member O⁴, and at its opposite end to a lever N², pivotally mounted at N³, and constructed at its opposite end to be operated upon by a cam wheel N⁴, mounted upon a spindle N⁵, provided with a gear N⁶, adapted to be turned by the pinion, or gear, O⁷, on the arbor, or spindle on which is mounted the alarm winding key O⁶. Gears N⁶ and O⁷ are indicated by dot and dash lines only as they form no part of my invention. It will be understood of course that the cam wheel N⁴, may be mounted upon an independent spindle, or arbor, or, if the construction permits, may be mounted upon one of the regular spindles of the clock mechanism and connected in any desirable manner so that it will be turned in the direction indicated by the arrow, when the alarm winding key O⁶, 80 is turned to wind the alarm. A spring N⁷, is mounted adjacent the points of the cam wheel N⁴, for the purpose of normally holding said wheel in a position to allow the end of the lever N², to always move into the position shown in full lines, and so as not to catch on a point of the cam wheel N⁴. A spring N⁸, is mounted adjacent the lever N², for the purpose of holding it in a position so that its opposite end will clear the cam 90 wheel N⁴, when the locking member O⁴, is in the "on" position, and to prevent its accidental movement. This spring N⁸, is not strong enough, however, to move the locking member O⁴, from the "off" to the 95 "on" position without the assistance of the cam wheel N⁴.

The operation of my invention will be clear from the drawing, taken in connection with the foregoing description, but may be 100 briefly described as follows:

We will assume that the alarm has just operated and that the person awakened thereby has moved the locking member O⁴, to the position shown in full lines, and has 105 thus locked the alarm against further operation. By my invention it is not necessary that the person should remember to unlock the alarm the next time he winds it, but in winding the alarm by means of the alarm key O⁶, he thereby also turns the cam wheel N⁴, through its operating connections with

said alarm key O^6 , and thus moves the lever N^2 , from the position shown in full lines to the position shown in dotted lines, automatically moving the locking member O^4 , 5 from the position shown in full lines to the position shown in dotted lines.

I am aware that my invention can be changed in many details to adapt it to alarm clocks of different constructions without departing from the spirit thereof and I do not therefore limit my invention to the particular embodiment thereof here shown for purposes of illustration, except as I may be limited by the hereto appended claims.

16 I claim:

1. In an alarm clock, in combination with a vibrating hammer, a manually operable cut-off member for holding said hammer against action, a link connected to said cut-off member, a pivoted lever connected to said link, and a cam connected to be operated with the winding of said alarm, said

cam being adapted to move said lever by a cam engagement therewith.

2. In an alarm clock, in combination with the alarm hammer, and the manually operable cut-off member thereof, a pivoted lever having one end connected with said cut-off member, a toothed, lever-operating wheel positioned to have a cam engagement with said lever, whereby to move the same as it is turned for automatically moving said cut-off member out of locking position, and means for automatically holding said toothed lever-operating wheel in proper stopped position relative to said lever, substantially as described.

Signed at Centralia, Washington, this 7th day of March, 1917.

ALPHONSO A. WOELFEL.

In presence of—

O. T. WEDMARK,
A. B. HUGHES.
